UNITED STATES PATENT OFFICE.

WILLET C. WELLS, OF FOSTORIA, OHIO.

CHAIN-WHEEL TEMPER.

SPECIFICATION forming part of Letters Patent No. 451,146, dated April 28, 1891.

Application filed September 15, 1890. Serial No. 365,061. (No model.)

To all whom it may concern:

Be it known that I, WILLET C. WELLS, of Fostoria, in the county of Seneca and State of Ohio, have invented certain new and useful

5 Improvements in Chain-Wheel Tempers; and I do hereby declare that the following is a full, clear, and exact description of the invention, which will enable others skilled in the art to which it appertains to make and use the same, 10 reference being had to the accompanying drawings, and to the figures of reference marked thereon, which form part of this specification.

This invention relates to a chain - wheel temper-screw adapted to be used more particularly upon machines for sinking gas or oil wells.

The object of the invention is to produce a device of the above description which shall be of such construction that all slack rope or 20 chain will be taken up, and which will at the same time admit of the rope or chain being readily fed out as rapidly as may be desired.

A further object is to produce a chain-wheel temper-screw which shall be simple of 25 construction, efficient and durable in use, and comparatively inexpensive of production.

With these objects in view the invention consists in the novel construction and combination of parts of a chain-wheel temper-screw, 30 as will be hereinafter fully described and claimed.

In the accompanying drawings, forming part of this specification, and in which like numerals of reference indicate corresponding 35 parts, I have illustrated one form of device embodying the essential features of my invention, although the same may be carried into effect in other ways without in the least departing from the spirit thereof; and in 40 these drawings—

Figure 1 is a side elevation of a well-boring machine, showing the different parts of the same and my temper - screw secured in place thereon. Fig. 2 is a similar view on an 45 enlarged scale, showing more particularly the temper-screw. Fig. 3 is a sectional view taken on line α α of Fig. 2, showing more particularly the worm for operating the temper-screw, and Fig. 4 is a top plan view showing the 50 manner in which the chain-wheel temper-screw is held in operative position.

Referring to the drawings, 1 designates a base, upon which is journaled in suitable bearings a drum 2, which is actuated by means of intermediate gears from a pulley 3. As 55 this mechanism forms no part of the invention, a detailed description of it is not thought necessary. Upon the said base are mounted standards 4, connected by means of cross-pieces 5, upon which is mounted a dovetailed 60 track 6, on which the chain - wheel temper-screw moves. This latter consists of a casting or frame 8, carrying a stud 9, on which is mounted a wheel 10, comprising a worm-wheel proper 11 and a chain-wheel 12, formed, preferably, integral therewith. The wheel is formed with a series of depressions or recesses 13, in which the flat sides of the links of the chain rest, while the alternate links engage a peripheral recess 14. The outer side 70 of the wheel is formed with a flaring portion 15, which serves as a guide to hold the chain 16 in place when in operation. Immediately below the worm-wheel is journaled a worm 17, which is actuated by means of a hand-wheel 18 to turn the said wheel in either direction. The lower portion of the casting 8 is formed with a perforated lug 19, to which connects the upper end of a pitman 20, the lower end of which connects with a crank 21 80 upon the drum-shaft. To the pitman is secured a cylinder or box 22, adapted to contain the chain, the length of which is equivalent to the length of one of the drill - stocks. To the upper end of the said chain is connected a rope 23, which passes over a pulley 24 and connects with the drill-stock 25. The other parts of the mechanism illustrated—such, for example, as the escape-pipe and casting—are not described, as it is not thought 90 necessary.

Having thus fully described my device, I will explain the manner of its operation. When the machine is in operation and it is desired to lower the drill, the operator simply 95 turns the hand-wheel 18 at each stroke of the crank 21, thereby feeding out as much chain as may be desired until the length of the chain in the box 22 is exhausted. Another section of drill-stock is then attached, the chain being uncoiled from the chain-wheel, the surplus chain returning to the box and recoiled 100

upon the chain-wheel, from which it is fed back as the drilling proceeds in the manner described.

It will be readily seen from the foregoing description that although this device is exceedingly simple of construction it may be operated with but a small amount of labor.

Having thus fully described my invention, what I claim as new, and desire to secure by Letters Patent, is—

1. In a chain-wheel temper-screw, the combination of a reciprocatory frame or casing, a combined worm and chain wheel carried thereby, and a worm adapted to engage the said wheel.

2. In a chain-wheel temper-screw, the combination of a reciprocatory frame or casing, a combined worm and chain wheel journaled thereto, and a worm adapted to operate the said wheel.

3. In a chain-wheel temper-screw, the combination of a reciprocatory frame or casing carrying a stud or projection, a combined worm and chain wheel journaled on said pro-

jection, and a worm adapted to operate the 25 said wheel.

4. In a chain-wheel temper-screw, the combination of a reciprocatory frame or casing, a combined worm and chain wheel journaled thereon, one end of which is formed with 30 teeth and the opposite end with a flaring portion, and a worm adapted to engage the said teeth.

5. In a chain-wheel temper-screw, the combination of a reciprocatory frame or casing 35 and a combined worm and chain wheel journaled thereon, one end of which is formed with a worm-wheel and the opposite end with a flaring portion, chain-engaging devices intermediate the wheel and flaring portion, and 40 a worm adapted to engage the said wheel.

In testimony that I claim the foregoing as my own I affix my signature in presence of two witnesses.

WILLET C. WELLS.
